UNITED STATES PATENT OFFICE.

EDWARD C. MOORE, OF YONKERS, NEW YORK, ASSIGNOR TO TIFFANY & CO., OF NEW YORK, N. Y.

DESIGN FOR JEWELRY-BOXES.

Specification forming part of Design No. 6,721, dated June 24, 1873; application filed June 14, 1873.

To all whom it may concern:

Be it known that I, EDWARD C. MOORE, of Yonkers, in the county of Westchester and State of New York, have invented a new and original Design for Paper-Boxes for Jewelry, &c., of which the following is a specification:

Figure 1 is a side elevation, and Fig. 2 is a top view, of a box constructed according to my design.

Similar letters of reference indicate corresponding parts.

The design consists of the oval form of the sides A and ends B, for boxes made of stiff paper, Bristol or straw board.

I claim as my invention—

The design for a jewelry-box, as herein described and shown.

EDWARD C. MOORE.
